FIRE BOMB

Asa Porter Prather and Ralph Russell, Georgetown, Ky., assignors of four-eighteenths to Otho Porter Prather, three-eighteenths to J. C. McKnight, and three-eighteenths to Thomas K. Shuff, all of Georgetown, Ky.

Application December 26, 1941, Serial No. 424,516

11 Claims.

(Cl. 102—65)

Our invention relates to fire bombs of a type comprising a frangible container filled with an inflammable liquid and ignited exteriorly to cause the contents to spread in flame upon impact between the projectile and the target. Such bombs may comprise a glass container having a wick wrapper saturated with inflammable liquid. The projectile is ignited by the thrower and manually thrown at the target to break the container and ignite its contents. Such bombs are efficient for the purpose intended but are difficult to handle, ignite and throw, particularly when enveloped in flame.

An object of our invention is to provide a fire bomb provided with a novel handle to facilitate manipulation and throwing of the bomb together with novel means for igniting the wrapper thereof by thumb pressure of the hand grasping the handle to afford protection against burning of the thrower, in addition to increasing the accuracy with which the fire bomb may be thrown.

A further object is to provide a fire bomb comprising a container filled with an inflammable liquid, wherein the container is enclosed in a dry wrapper and provided with a handle, together with a primer supply of inflammable liquid incorporated in the handle structure and released about the wrapper preparatory to the throwing of the bomb, wherein novel means are incorporated for igniting the saturated wrapper by thumb pressure of the hand grasping the handle.

In the accompanying drawings:

Figure 1 is an elevational view of a fire bomb in accordance with our invention;

Figure 2 is a sectional view taken along the line 2—2 of Figure 1 illustrating the primer container in its normally intact condition;

Figure 3 is a similar view but illustrating the primer container opened for spilling the primer fluid upon the wrapper;

Figure 4 is a sectional view taken along the line 4—4 of Figure 2;

Figure 5 is a sectional view taken along the line 5—5 of Figure 2; and

Figure 6 is a sectional view taken along the line 6—6 of Figure 2.

In the embodiment selected for illustration, we make use of a container 10 which may comprise any suitable frangible material for containing the inflammable liquid. Gasoline is entirely suitable for an inflammable liquid. Figures 2 and 3 illustrate the container 10 in the nature of a conventional Mason jar provided with a cover 12 having a screw thread connection at 14 with the neck 16 of the container. A gasket 18 is interposed between the screw cap and the container flange 20 to render the container leakproof to the end that the bombs may

be handled in a dry condition up to the time of use.

To the cover 12 is fixedly secured a tubular handle 22 having a flange 24 provided with legs 26 fixedly secured thereto and to the cover 12, as by welding. Inside the handle 22 is mounted a primer container 28 provided with a screw neck 30 at its lower end for threaded connection with a screw cap 32 fixedly secured to the cover 12. A gasket 34 is interposed between the end of the neck 30 and the cap 32 to provide a liquidtight connection. Container 28 may also contain gasoline. A compression spring 36 is interposed between the cover 12 and the shoulder 38 on the neck 30.

To the upper end of the container 28 is fixedly secured a body 40 having a slot 42 within which is slidably arranged a tongue 44 fixedly connected with an end cap 46 rotatably mounted on the flange-like formation 48 on the handle 22. The neck 30 of the container 28 may be disconnected from the cap 32 through rotation of the primer container relative to the cap. Such rotation is obtained through relative rotation of the end cap 46 and the handle 22. During such rotation, the handle 22 is grasped in one hand and the end cap 46 rotated with the other hand, with the bomb held vertically so that the liquid in the container 28 will spill downwardly on the container 10 to saturate the wick or wrapper 50. The legs 26 are relatively narrow and spaced considerable distances apart so that the primer liquid will be distributed uniformly on the wrapper 50.

After saturation of the wrapper 50, the wrapper is ignited through manipulation of an igniter 52, which comprises a stationary file or friction member 54 engaged by a friction match 56 carried at one end of a thumb strap 58 pivotally connected at 60 with the handle 22. A compression spring 62 is interposed between the handle 22 and the thumb strap 58 to normally hold the latter in the position of Figure 2.

Figure 3 illustrates the primer container 28 disconnected from its cap 32 and with the thumb strap 58 pivoted to its opposite extreme position, during which movement the inflammable liquid spills on and about the friction member 54 is ignited.

To afford additional protection against burning of the thrower, a plate 64 is secured to the flange 24, which plate is provided with a depending flange 66 of considerably larger diameter than the cap 12 to provide a circumferential space 68 through which the priming liquid is spilled upon the wrapper 50. Thus the plate 64 and its flange 66 provide a fire guard. The friction member 54 is secured to the flange 66, while the plate 64 is provided with a slot 70 to accommodate the thumb strap 58.

A fire bomb of the type described comprises a unit which is maintained in a dry condition up to the time of use. This facilitates handling and manipulation of the bomb. The igniter is conveniently actuated by thumb pressure, and the priming liquid is spilled on the wrapper 50 only at the moment of use. The hands of the thrower need not become dangerously or objectionably near the burning wrapper, and the priming liquid is spilled in such manner as to afford complete protection against spilling of the liquid upon the hands of the thrower. In addition, the handle facilitates throwing of the bomb so as to increase the marksmanship of the thrower. The fire bomb can not be accidentally ignited 15 since the wrapper 50 is normally in a dry condition. The lighting action must be delivered and preconceived. The thrower is protected from all contact with fumes or inflammable material, thereby greatly reducing chances for possible 20 burns.

A bar 12 is welded to diametrically opposed legs 26 and constitutes an effective anchor for the cap 32, the bar 12 lying adjacent the cap 12.

Without further elaboration, the foregoing will so fully illustrate our invention, that others may, by applying current knowledge, readily adapt the same for use under various conditions of service.

We claim:

1. A manually thrown fire bomb comprising 30 an impact frangible container for an inflammable liquid, a wick means exteriorly of and adjacent the container, a handle attached to said container, a primer container for an inflammable liquid mounted on said handle adjacent said 35 wick means, means for opening the primer container to spill the inflammable liquid therein on said wick means, and an igniter means for igniting said wick means.

2. A manually thrown fire bomb comprising an 40 impact frangible container for an inflammable liquid, a wick means exteriorly of and adjacent the container, a handle attached to said container, a primer container for an inflammable liquid fixedly related to the container adjacent 45 said wick means, means for opening the primer container to spill the inflammable liquid therein on said wick means, and an igniter means for said wick means accessible by a finger of the hand grasping said handle.

3. A manually thrown fire bomb comprising 50 an impact frangible container for an inflammable liquid, a hollow handle attached to the container, a wick means on said container, a primer container for an inflammable liquid mounted in the handle, said handle being provided with a 55 spillway for spilling the liquid in the primer container upon said wick means, means for opening said primer container to spill the liquid therefrom, and an igniter for said wick means.

4. A manually thrown fire bomb comprising an impact frangible container for an inflammable liquid, a hollow handle attached to the container, a wick means on said container, a primer container for an inflammable liquid mounted in the handle, said handle being provided with a spillway for spilling the liquid in the primer container upon said wick means, means for opening said primer container to spill the liquid therefrom, and a friction igniter for 60 said wick means accessible for actuation by a finger of the hand grasping said handle.

5. The invention described in claim 1 wherein 70 said primer container comprises two parts de-

tachable one from the other through relative rotation of the parts, and means on said handle connected with one of said parts to impart rotation thereto relatively to the other part.

6. The invention described in claim 1 wherein 10 said primer container comprises two parts detachable one from the other through relative rotation of the parts, means on said handle connected with one of said parts to impart rotation thereto relatively to the other part, and spring means acting on said parts to space one from the other upon separation thereof.

7. The invention described in claim 1 wherein 15 there is provided a flame guard located between the frangible container and said handle.

8. A manually thrown fire bomb comprising 20 an impact frangible container for an inflammable liquid, a hollow handle attached to the container, a wick means on said container, a primer container for an inflammable liquid mounted in the handle, said handle being provided with a spillway for spilling the liquid in the primer container upon said wick means, means for opening said primer container to spill the liquid therefrom, an igniter for said wick means, and a flame guard located between the frangible container and said handle.

9. The invention described in claim 1 wherein 25 said primer container comprises two parts detachable one from the other through relative rotation of the parts, means on said handle connected with one of said parts to impart rotation thereto relatively to the other part, and a flame guard located between the frangible container and said handle.

10. The invention described in claim 1 wherein 30 in said primer container comprises two parts detachable one from the other through relative rotation of the parts, means on said handle connected with one of said parts to impart rotation thereto relatively to the other part, and a flame guard located between the frangible container and said handle, said igniter means being located between said flame guard and the frangible container and having an actuated element located between the flame guard and said handle.

11. A manually thrown fire bomb comprising 35 a glass container for an inflammable liquid, a first cap having a threaded connection with the container, a tubular handle, legs fixedly connecting said handle with said first cap, a second cap fixedly mounted on said first cap, a wick wrapper on said glass container, a second container inside said handle for an inflammable liquid, said second container having a threaded connection with said second cap, a body on said second container inside said handle, a member rotatably mounted on said handle, a tongue slidable in said slot to detach the second container from the second cap through rotation of said member relatively to the handle, a spring interposed between the second container and the first cap to move the second container away from the second cap upon threaded disconnection thereof to spill the liquid in the second container upon said wick wrapper, a friction match means for igniting said wick wrapper having an actuating member accessible by a finger of the hand grasping said handle, and a flame guard interposed between said handle and said first container.

ASA PORTER PRATHER,
RALPH RUSSELL
